METHOD AND APPARATUS FOR THE TREATMENT AND
UTILIZATION OF SUPERHEATED STEAM

Filed July 13, 1923

UNITED STATES PATENT OFFICE.

JOHN R. McDERMET, OF JEANNETTE, PENNSYLVANIA, ASSIGNOR TO ELLIOTT COMPANY, OF PITTSBURGH, PENNSYLVANIA, A CORPORATION OF PENNSYLVANIA.

METHOD AND APPARATUS FOR THE TREATMENT AND UTILIZATION OF SUPER-HEATED STEAM.

Application filed July 13, 1923. Serial No. 651,302.

The present invention relates broadly to power plant practice and equipment, and more particularly to a method and apparatus for the treatment of superheated steam to reduce it to a condition of saturation, and for the utilization of the saturated steam so produced.

In my co-pending application Serial No. 651,301, filed July 13, 1923, I have disclosed and claimed a method and apparatus for desuperheating steam to reduce the superheat therein to a condition of saturation whereby the characteristics of such steam causing it to behave very much like a perfect gas are destroyed, and the latent heat, which accomplishes the major transfer of heat in heater condensation, is rendered immediately available.

The present invention has for one of its objects the production of an improved organization of apparatus embodying a heater and a desuperheater, whereby efficient desuperheating of the steam and efficient heater performance are obtained. While the present invention is especially useful in connection with turbine installations, it will be understood that the utility of the invention is not limited in this respect.

At the present time, there is a tendency in power station operation to employ steam pressures considerably higher than has been customary in the past. Heretofore, the range of steam pressures has been up to 350 pounds per square inch as a maximum, while now these pressures frequently extend to 550 pounds per square inch. On account of the strength of materials, however, it has not been expedient to increase total steam temperatures much beyond 750° F. The expansion of steam in a turbine through this pressure range from, for instance, 550 pounds gage to one pound absolute, with such a moderate amount of initial superheat as the strength of materials imposes, produces very wet steam which is inefficient during part of a turbine expansion.

In order to obviate this objection to the wet steam, a reheat cycle has been developed in which steam with an initial temperature of 750° F. and 550 pounds pressure, for example, is brought through the turbine and expanded to a gage pressure of 200 pounds. It is then withdrawn from the

turbine, again superheated, and subsequently returned as superheated steam to complete the expansion.

Considerations of heat economy in power generation indicate the advisability of abstracting steam from various stages of the main turbine for feed water heating. With the steam cycle involving the resuperheat at an intermediate point in the expansion, the usual stage connections now exhibit superheated steam, whereas under the previous cycle of operation the steam on the stage connections was saturated. This superheated steam, as such, produced with present day turbine designs, does not give efficient heater performance. The invention therefore embodies the treatment of this steam in such manner as to insure high conductivity.

In the accompanying drawings there is shown, for purposes of illustration only, in a more or less diagrammatic manner, a preferred embodiment of the present invention, it being understood that the drawings do not define the limits of the invention, as changes may obviously be made in the construction and operation disclosed without departing from the spirit of the invention or scope of my broader claims.

In the drawings Figure 1 is a view partly in side elevation, partly broken away, and partly in section, illustrating one embodiment of the invention, and Figure 2 is a transverse sectional view through the water manifold of Figure 1 illustrating the manner of distributing water to the desuperheater. This organization of apparatus, in accordance with the present invention, may comprise a heater 2, preferably of the closed type, having a condensate outlet 3 and a cooperating desuperheater 4. This desuperheater, which may be of the construction covered in my co-pending application before referred to, has an inlet 5 and an outlet 6, the inlet and outlet, respectively, preferably being at substantially diametrically opposite sides of the desuperheater chamber 7. Within this chamber, and so located as to intercept the path of travel of the steam, is a porous body 8 pervious to the passage of steam and preferably confined between perforated plates 9.

While the particular construction of the

desuperheater may be varied, I have found that efficient results may be obtained by employing perforated Monel plates for the baffles 9 and wire mesh of Monel wire for the body 8. This entire body may be in the form of a cartridge adapted to be bodily inserted in or removed from the chamber 7.

The outlet 6 leads through a suitable connection to the vapor inlet 10 of the heater 10 2, while the condensate outlet 3 from the heater leads to a manifold 11 provided with a series of perforations or nozzles 12 so positioned as to supply the condensate to the porous body 8.

15 In operation of the apparatus, it will be apparent that superheated steam passes from the inlet 5 through the porous body 8 to the heater, wherein it gives up its heat to the feed water supplied thereto, as is customary in the art, and is condensed. The amount of condensate so formed will bear a definite relation to the amount of steam supplied to the heater. This condensate will in turn pass to the desuperheater 20 25 through the nozzles 12 and maintain a film of water over the surface of the porous body therein. This water, supplied for desuperheating purposes, will in large part be evaporated by the superheat in the steam, thereby increasing the total volume of the steam while decreasing the total temperature, but without reducing the pressure. The steam therefore leaves the desuperheater as saturated steam, yielding considerably 30 35 higher conductivity than would otherwise be possible, as the latent heat is immediately available for heating purposes within the heater.

In the event of any excess in the amount 40 of water supplied to the desuperheater, such excess may easily drain from the apparatus through the connection 13.

This organization of apparatus has been found to be highly efficient from a stand-point of installation and performance. Where the water required for desuperheating is brought to the desuperheater by means of an independent external connection, as has heretofore been contemplated, 45 50 there has been considerable risk due to the possibility of any excess of water flowing back into the turbine. As large steam turbines of the type now being installed frequently cost in the neighborhood of a million dollars, the risk involved becomes considerable. By the present invention, this 55 60 risk is entirely eliminated, as the amount of desuperheating water supplied to the desuperheater bears a definite relation and is automatically proportioned to the amount of steam to be desuperheated and to the turbine load. This is necessarily true for the reason that the only source of water for the desuperheater is condensate from the heater, and the only source of this condensate

is steam which has first passed through the desuperheater. When the steam is shut off from the turbine, necessarily it will be shut off from the extraction connection and no water supply to the desuperheater will be available. This constitutes one very advantageous feature of the present invention. 70

Furthermore, the presence of moisture, cold steam lines, etc., will provide sufficient wet steam at the start-up to enable the apparatus to come immediately into operation. Furthermore, it is customary, due to operating necessity, to start the complete unit on saturated steam and subsequently create the condition of superheat gradually after 80 the apparatus is in operation. It will be apparent, therefore, that the desirable self-starting features of the apparatus are entirely automatic.

I claim:

1. Power plant apparatus comprising a desuperheater having an inlet for superheated steam, an outlet for desuperheated steam, and a heater communicating with said outlet and having means for supplying 90 to said desuperheater desuperheating water resulting from the condensation of said desuperheated steam.

2. In the method of treating and utilizing steam, the steps consisting in supplying 95 superheated steam to a desuperheater, and supplying to said desuperheater desuperheating water not in excess of an amount equal to the condensate which could be formed from the steam fed to the desuperheater, and substantially equal in amount to the condensate which could be formed from the steam fed to the desuperheater.

3. In the method of treating and utilizing steam, the steps consisting in passing 100 superheated steam through a desuperheater and the resulting saturated steam into a heater, condensing the steam in the heater, and feeding condensate from the heater to the desuperheater for desuperheating purposes.

4. In the method of treating and utilizing steam, the steps consisting in feeding 105 superheated steam to a desuperheater, feeding the steam from the desuperheater to a heater in saturated condition, condensing the steam in the heater and supplying to said desuperheater for desuperheating purposes only the condensate formed by the condensation of said steam in the heater.

5. Power plant apparatus comprising a closed heater, a desuperheater supplying steam thereto, and means for bringing condensate from the heater into contact in divided form with steam passing through the 115 desuperheater.

6. Power plant apparatus comprising a closed heater, a desuperheater having its outlet leading to the vapor inlet of the heater, means intersecting the flow of steam through 120 125

the desuperheater, said means having interstitial flow openings for bringing condensate from the heater into contact with the steam passing through the desuperheater, and means for leading condensate to said means.

7. Power plant apparatus comprising a closed heater and a desuperheater supplying steam thereto, said heater having a condensate outlet leading to the desuperheater and constituting the sole source of liquid supply to the desuperheater, and means pervious to the passage of steam and intersecting the steam flow for receiving said condensate and bringing the steam and the condensate into intimate contact.

8. Power plant apparatus comprising a heater, a desuperheater, supplying steam thereto, said heater having a condensate outlet leading to the desuperheater, and means in said desuperheater pervious to the passage of steam and intersecting the steam flow through the desuperheater for receiving condensate from said outlet and bringing the condensate and steam into intimate contact.

9. Power plant apparatus comprising a closed heater, a desuperheater having its outlet leading to the vapor inlet of the heater, and of sufficient size to conduct to the heater all of the steam received by the desuperheater plus an additional amount represented by the evaporation of water within the desuperheater, and a condensate outlet for supplying desuperheating water from the heater to the desuperheater.

10. Power plant apparatus comprising a closed heater, a desuperheater having its outlet leading to the vapor inlet of the heater and of sufficient size to conduct to the heater all of the steam received by the desuperheater plus an additional amount represented by the evaporation of water therein, said heater having a condensate outlet for supplying desuperheating water to the desuperheater, and means within the desuperheater pervious to the passage of steam for receiving said desuperheating water and bringing the same into intimate contact with the steam.

11. Power plant apparatus comprising a desuperheater having an inlet for superheated steam, and means for supplying to said desuperheater in contact with the superheated steam desuperheating water in the form of condensate formed from said desuperheated steam and in an amount such that the superheat of the steam is destroyed without substantially decreasing the heat quantity of the steam.

12. Power plant apparatus comprising a desuperheater having an inlet for superheated steam, an outlet for saturated steam and a heater for receiving desuperheated steam from said outlet, said heater having a condensate outlet conducting such condensate as desuperheating water in divided condition to said desuperheater in contact with the steam.

13. In the method of treating and utilizing steam, the steps consisting in desuperheating steam while maintaining substantially as great a heat quantity in vapor state, condensing the desuperheated steam by utilizing the same for heating purposes, and supplying condensate so formed for desuperheating purposes.

14. In the method of treating and utilizing steam, the steps consisting in desuperheating superheated steam while maintaining substantially as great a heat quantity in vapor state, passing the desuperheated steam to a heater, condensing the steam in said heater, and supplying the condensate so formed for desuperheating the steam supplied to the heater.

15. In the method of treating and utilizing steam, the steps consisting in desuperheating superheated steam without condensation thereof, passing the desuperheated steam to a heat exchanger and supplying the condensate from said heat exchanger to the desuperheater for desuperheating the steam supplied to the heat exchanger.

In testimony whereof I have hereunto set my hand.

JOHN R. McDERMET.
